STRIP LABEL

Stephen Bardos, South Norwalk, Conn., assignor
to J. and J. Cash, Incorporated, South Nor-
walk, Conn.

Application April 19, 1932. Serial No. 606,189

9 Claims. (Cl. 139—384)

This invention relates to strip labels; and more particularly, a strip adapted to be divided into a plurality of labels by cutting.

The principal object of this invention resides in so forming the strip that tucks or folds are produced so that each label when severed from the strip will have its adjacent severed edges turned under so that the label may be readily stitched to the garment or article without the

necessity for turning the edges under, which is the common practice. Heretofore, labels have been formed in strips with a space formed between the same so that the operator can sever the labels in securing the same to the article. Since cutting the strip will leave unfinished edges, it becomes necessary to turn the unfinished edges under the label and stitch the same in position. This will prevent unraveling of the label, and present a much superior appearance.

The turning of the unfinished edges under the label and securing the same in place is a very tedious operation and requires the expenditure of a great amount of time. In some isolated cases, tucks have been formed in the strip during the weaving process, or by a sewing machine after the strip has been finished, but these methods are inadequate since as soon as the labels are severed from the strip, there is nothing to hold the tucks in place, except the previous folding, and these can easily become disarranged from beneath the label. This is even more true where pleats are used as any stretching will quickly remove the pleats.

In my invention, I provide positive means for holding the turned-under edges in position so that no matter how the label is treated, the edges will always resume a position beneath the label. This permits the label to be severed from the strip and placed in position without any additional folding so that the operator may quickly stitch the same in place.

Other objects will be disclosed in the specification and claims forming a part of this application.

In the drawing:

Figure 1 is a perspective of a strip of unsevered labels;

Figure 2 is a perspective view of the rear face of the strip disclosed in Figure 1;

Figure 3 is an enlarged diagrammatic view showing the positioning of the elastic in the label; and

Figure 4 is a perspective of one of the labels after it has been severed from the strip.

Referring to the drawing, in which similar parts

are designated by like numerals throughout, numeral 5 designates a strip of woven labels 6. Although I have shown woven labels, this is merely illustrative, as my invention is applicable whenever separately defined panels are to be separated from a fabric strip by a cutting operation. The strip 5 has finished side edges 7 and double pleats 8 between each label 6. The double pleats 8 form a cutting zone 9 which the operator severs in detaching the label.

During the pleat forming operation, elastic 10 is woven into the strip 5 extending through the double pleats 8 to the adjacent labels. The elastic 10 is anchored in the label by being woven therein, but is exposed in bridging the pleats 8. It is anchored again in the cutting zone 9 by being woven into the strip 5 so that the cutting of this zone will not interfere with the proper functioning of the elastic. The resulting elasticity does not extend beyond the immediate edge of the label 6 adjacent the pleats 8 since the non-elastic material constituting the labels prevents any stretching, even though the elastic extends the length of the strip. Thus the labels retain their shape and are not subject to any distortion or stretching other than is present in the usual label.

The labels are woven in the usual manner, except that strands of elastic, under tension, are woven into the strip 5. At designated points where the pleats or folds are to occur, the strands of elastic are intentionally exposed. It must also be realized that the strip or piece is woven flat. Upon the strip or piece 5 being removed, the strip 5 will pucker at the places where the elastic has been exposed forming the folds or pleats 9. This construction is more clearly shown in Figure 3. The outer ends 11 of the strip 5 will form a single pleat, whereas double pleats will be formed intermediate the labels, the portion between the pleats forming a cutting zone 9.

As actually used, the labels will be severed in the zone 9 adjacent the first pleat. Since the elastic 10 extends throughout the strip 5, there will be a certain amount of pull in both directions, but since the label portion is wider than the severing zone 9, the elastic 10 will have a tendency to pull the pleat 8 under the label. Upon the severing of the label, the action of the elastic 10 will be accentuated since the pull in the opposite direction has been largely eliminated, and the flap 12 extending beyond the pleat 8 will be more completely pulled beneath the label. The label can then be readily secured in position on the garment or other article to be labeled. The

severing operation will be repeated in each zone as labels are needed.

By placing a few strands of elastic in the strip, the label is resilient only at the pleats, and always assures the maintenance of the pleat in the desired relation to the label. In using the word "pleats", it is to be understood that I am not limiting myself to this term, but the same would apply to loops, tucks, hems, folds, or the like, provided they come within the scope of my invention.

Although for illustrative purposes, I have illustrated a woven label and the elastic passing through the entire strip, it is obvious that my invention is not restricted to the form shown, but is broad enough to cover all structures coming within the scope of the appended claims, and that the elastic might be only adjacent the pleats instead of extending throughout the strip.

20. What I claim is:

1. A fabric strip divided into a plurality of parallel panels intended for separable use, said strip having folds between said panels, a cutting zone between said folds, resilient means extending through said strip and forming a part thereof, said resilient means exterior of said folds while the strip remains unsevered and causes the edges of the folds to turn inwardly upon the panels being severed and adapted to maintain said folds in a predetermined position.

2. A strip of connected fabric labels each two labels in said strip having a spaced pair of parallel pleats located between them in inturned relation to said labels, resilient means for maintaining said pleats in inturned position and draw the edges inwardly upon being severed.

3. A label comprising inturned folds at two of its edges, resilient means passing through said folds to maintain said folds in inturned position.

4. A label having resilient strands forming a

part thereof, and folds at two of its edges, said resilient strands passing through said folds.

5. A fabric strip divided into a plurality of panels having resilient material therein, cutting zones between said panels, parallel folds in said cutting zones between said panels, said folds of non-resilient material, strands of said resilient material passing through and bridging said folds.

6. A fabric strip divided into a plurality of panels intended for separable use, said strip having parallel folds between said panels, a cutting zone between said folds, resilient strands anchored in said panels and said cutting zone and free from said folds between said panels and said cutting zone causing the edges of said folds to turn inwardly.

7. A fabric strip comprising a plurality of non-resilient parallel panels intended for separable use, said strips having folds between said panels, and a cutting zone between said folds, resilient strands under tension extending the length of said strip and forming a part of said panels and cutting zones, said strands being free from said folds and causing the edges of said folds to turn inwardly.

8. A fabric strip divided into a plurality of label panels with intervening anchoring zones, and edge forming zones at the sides of said anchoring zones, said fabric being formed with rubber strands tensioned during the weaving, interwoven with said panels and said anchoring zones and bridging said edge forming zones, whereby when the tension on the strands is released, they will contract, drawing the edge forming zones into corrugations, the free ends in which said strands are anchored being turned down beneath said panels, when severed, forming folded edges.

9. Label comprising a fabric panel having edge portions and means for elastically biasing said edge portions to positions underlying said panel.
